UNITED STATES PATENT OFFICE

126,493

DESIGN FOR A DRESS ENSEMBLE

William Clion, Brooklyn, N. Y.

Application March 5, 1941, Serial No. 99,354

Term of patent 3½ years.

To all whom it may concern:

Be it known that I, William Clion, a citizen of the United States, residing in Brooklyn, New York, in the county of Kings and State of New York, have invented a new, original, and ornamental Design for a Dress Ensemble, of which the following is a specification, reference being had to the accompanying drawings, forming part thereof.

The cape is integrally attached to the jacket member of the ensemble.

I claim:

The ornamental design for a dress ensemble, substantially as shown and described.

WILLIAM CLION.
